UNITED STATES PATENT OFFICE.

HARRY D. MORTON AND MORGAN PARKER, OF NEW YORK, N. Y.

METHOD OF MAKING NEEDLE-AND-SUTURE ASSEMBLY.

Application filed July 30, 1925. Serial No. 46,937.

The following is a description of a needle-and-suture assembly and methods of and means for making the same embodying our invention in the form and manner at present preferred by us; but it will be understood that various modifications and changes may be made without departing from the spirit of our invention and without exceeding the scope of our claims.

- 10 In an application for United States Letters Patent No. 1,558,037, filed June 17, 1925, Serial No. 37,599, Harry D. Morton disclosed a surgical needle-and-suture assembly and methods of making the same, said invention comprising a needle having formed in its shank a recess in substantial axial alignment with said needle, in which recess a suture is adapted to be anchored. The present invention relates to specific methods of and means 20 for attaching such a suture, which we have found may be effectually anchored by expanding, when in a dry state and by the action of heat, the portion thereof inserted in said recess.
- 25 Our invention will best be understood by reference to the accompanying drawings, in which we have illustrated the preferred manner of carrying out our invention, and in which Fig. 1 shows, partly in elevation and partly in section, a needle having formed in its shank a substantially axial recess, which may be generally cylindrical in shape and which may have a constricted neck or opening; Fig. 2 shows in section an enlarged view 30 of the shank end of said needle, with a tapered end portion of a suture inserted therein; Fig. 3 shows in section the same view as that shown in Fig. 2, after the inserted portion of the suture has been expanded by the 35 action of heat, so that it conforms, more or less completely, to the shape of the recess—whereby it becomes anchored therein; and Fig. 4 shows means for holding the needle-and-suture assembly in position and for applying heat to the shank portion of the needle while so held, in order that the heat may be conducted to and expand the inserted 40 end of the suture.
- 45 Like reference characters indicate like parts throughout the drawings.

Referring to the drawings: 1 is a needle, which may be of any desired body size and shape; 2 is a recess formed in the shank thereof in any suitable manner, such as by drilling—said recess initially being preferably cylindrical or slightly tapering in

shape and of such diameter, relative to the outside diameter of the shank, as to leave only a thin surrounding wall; 3 is the neck or opening of the recess, after having been 50 constricted, as by swaging or spinning, to a diameter smaller than the diameter of the body of the recess; and 4 is a catgut suture, such as is commonly employed in surgery. In order to strengthen the needle at the 55 juncture of the solid portion of the shank and the shell portion thereof formed by the wall of the recess, we preferably leave a fillet between the bottom of the recess and the wall thereof. In order to facilitate the inward 60 swaging or spinning of the upper portion of the recess wall, we may initially taper this wall from the bottom toward the top thereof.

Referring to Fig. 4: 5 represents a support 70 for the needle, comprising an electrical conductor (preferably made of copper), which support is electrically connected by line 6, through adjustable resistance 7, to one terminal of secondary winding 8 of transformer 9, having primary winding 10. The opposite 75 terminal of secondary winding 8 is connected by line 11 to switch member 12 (formed of carbon or other suitable conducting material), mounted upon insulator 13, attached to push-rod 14, vertically movable in bearing 22, attached to which bearing is insulator 23, carrying switch member 15, connected by line 16 to lever 17 (comprising an electrical conductor and being preferably formed of copper), pivotally mounted upon 80 fulcrum 18. The right-hand end of lever 17 carries pin 19, loosely fitting in and electrically insulated from the yoke portion, 20, of push-rod 14. Expansion spring 21 normally holds push-rod 14 against cam 24, 85 whereby the left-hand end of said lever 17 is maintained out of contact with needle 1, and whereby switch members 12 and 15 are separated, leaving the electric circuit open.

The mode of operation of the device of 90 Fig. 4 is as follows: The needle, with the suture end inserted, is manually held in position on support 5, and cam-shaft 25 is rotated in any well-known manner, as by a 95 pedal operating a clutch to connect shaft 105 25 with a driving motor or other source of power. The rotation of cam 24 in the direction indicated by the arrow forces push-rod 14 upward in its bearing 22, bringing left-hand end of lever 17 into contact with 100 needle 1 and closing the electric circuit 110 through contact of switch member 12 with

switch member 15. The high resistance of the thin shell of the shank portion of needle 1, relative to the resistance of conductors 5 and 17, quickly results in the heating of the 5 walls of the recess and of the end of the suture inserted therein. We have found that when catgut is subjected to a considerable degree of heat, it very quickly expands laterally—the increase in diameter being as 10 much as 75% and even more. This expansion is permanent, the heat appearing to produce a marked change in the structure of the catgut, rendering the same hard and tough, like horn. The best results seem to 15 be obtained when a high degree of heat is applied for a very brief period of time—say one or two seconds. Under these conditions the expanded portion of the catgut is apparently forced with considerable pressure 20 against the wall of the recess, and this pressure, acting in conjunction with the construction of the neck of the recess, affords a very effectual anchoring. The change in 25 the structure of the catgut, resulting from the operation of our invention, renders it peculiarly resistant to attempts to withdraw the suture from the recess. If the heat applied to the inserted end of the catgut be too great, or if such end be subjected to the 30 action of a lesser degree of heat for too long a time, the material is weakened. We therefore provide means, comprising adjustable resistance 7, for controlling the degree of heat which may be applied to the suture; 35 and we regulate the time during which it is exposed to heat action by varying the speed of shaft 25 in any well-known manner. This time of exposure may also be governed by employing cams of different contours. 40 We are thus enabled to subject the suture to the precise degree of heat and period of exposure which experience may show will produce the best results with the particular needle and suture materials. We are thus 45 able not only to effect the expansion of the inserted end of the suture with nicety, but at the same time to avoid drawing the temper of the shank portion of the needle. The advantages of employing a needle which is 50 hardened and tempered throughout are set forth in the aforesaid application of Harry D. Morton.

We preferably taper the end of the suture in order to facilitate the inserting of the 55 end thereof in the constricted recess. This may be accomplished by holding a portion of the suture rigidly, as in a clamp, and bringing a projecting end (about $\frac{1}{16}$ inch or less in length) thereof into contact with 60 a rapidly revolving abrasive surface which is simultaneously rotated around such projecting end. The end of the suture is thereby ground or abraded to the desired form. 65 Due to the brief exposure required to produce a considerable expansion of the insert-

ed end of the suture and to the hardening and toughening effect resulting from the application of heat, our invention comprises simple, effective and inexpensive means whereby a catgut suture may be permanent- 70 attached to a surgical needle. The advantages, in the art of surgery, of attaching a suture to a needle by anchoring said suture in an axial recess formed in the end of the shank of such needle are fully set forth in 75 the application of Harry D. Morton, hereinabove referred to.

It will be apparent to those skilled in the art that our invention may be carried out with recesses of other forms than that illustrated in the drawings. For example, the wall of the recess may be gradually (instead of abruptly) tapered; this wall may be cylindrical throughout its length, and may be tapped with a screw thread to give 85 both large and small internal diameters for anchoring purposes; or the inside of the recess wall may be otherwise scarified in such a manner as to provide, in conjunction with the method of expanding the suture which 90 we disclose, an adequate anchorage.

It is sometimes convenient for the surgeon, in drawing such a suture through tissue, to tilt the needle so that it is out of alignment with the suture. In order to prevent the outer edge of the recess wall from cutting the suture, under these conditions, we preferably round such edge.

It is to be understood that needle-and-suture assemblies made in accordance with 100 our invention are to be hermetically sealed and sterilized in the usual manner, and that each such assembly is to be employed in a single surgical operation only.

What we claim as new and desire to secure 105 by Letters Patent of the United States is:

1. The method of attaching a suture to a needle which consists in forming in said needle a recess constricted in diameter near the opening thereof, inserting an end of the 110 suture in said recess and applying heat to the wall of said recess, whereby the inserted portion of said suture is expanded.

2. The method of attaching a suture to a needle which consists in forming a recess in 115 the shank of the needle, constricting the neck of said recess, inserting an end of the suture in said recess and applying heat to such inserted portion whereby it is expanded.

3. The method of attaching a suture to a 120 needle which consists in forming a recess in the shank of the needle, inserting an end of the suture in said recess, and expansively anchoring the same therein by the action of heat.

4. The method of attaching a suture to a needle which consists in forming in said needle a recess having an internal diameter some 125 part of which is greater than its neck diameter, inserting a portion of the suture in 130

said recess, and expanding such inserted portion by the action of heat.

5. The method of making a needle-and-suture assembly which consists in forming a recess in the needle, hardening and tempering said needle, inserting an end of the suture in said recess and anchoring the same therein by the action of heat applied to such inserted portion.

10. 6. The method of making a needle-and-suture assembly which consists in forming a blind recess in the shank of a needle, hardening and tempering said needle, inserting an end of the suture in said recess and anchoring the same therein by the action of heat applied to said needle.

7. The method of attaching a suture to a needle which consists in inserting an end of said suture in a recess formed in said 20 needle, applying heat to such inserted portion to expand the same, and automatically controlling the degree of heat and the time of exposure thereto.

25 8. The method of attaching a suture to a needle which consists in inserting an end of said suture in a recess formed in said needle, applying heat to such inserted portion to expand the same, and electrically regulating the degree of such heat.

9. The method of attaching a suture to a 30 needle which consists in inserting an end of said suture in a recess formed in said needle and producing pressure between such inserted portion and the wall of said recess by the action of heat.

35 10. The method of making a needle and suture assembly which consists in inserting an end of a suture element in a recess formed in a needle element and attaching said elements by the action of heat applied to the 40 wall of said recess.

11. The method of attaching a suture element and a needle element which consists in inserting an end of the suture element in an 45 opening formed in the needle element, including said needle element in an electric circuit, and applying to said suture element heat generated by the electrical resistance of said needle element.

12. The method of making a needle and 50 suture assembly which consists in inserting an end of a suture element in a recess formed in a needle element and attaching said elements by the action of heat of a degree below the annealing temperature of said needle element.
